United States Patent Office

Des. 195,408
Patented June 11, 1963

195,408

VIDEO TELEPHONE CONSOLE

Robert E. Prescott, Rumson, N.J., assignor to Bell Telephone Laboratories, Incorporated, New York, N.Y., a corporation of New York

Filed Dec. 18, 1961, Ser. No. 67,932

Term of patent 14 years

(Cl. D26—14)

FIG. 1

FIG. 2

FIG. 3

FIG. 1 is a perspective view of a video telephone console showing my new design, with a cord, telephone and video picture, shown in broken lines for illustrative purposes;

FIG. 2 is a top view of my new designs; and

FIG. 3 is a side view thereof.

The essential features of the console are shown in full lines thereon.

I claim:

The ornamental design for a video telephone console, substantially as shown and described.
